CLAIM

The ornamental design for a retractable bayonet, as shown and described.

DESCRIPTION

FIG. 1 is a perspective view of a retractable bayonet in a closed configuration;

FIG. 2 is a front elevational view of the retractable bayonet shown in FIG. 1;

FIG. 3 is a rear elevational view of the retractable bayonet shown in FIG. 1;

FIG. 4 is a left side elevational view of the retractable bayonet shown in FIG. 1;

FIG. 5 is a right side elevational view of the retractable bayonet shown in FIG. 1;

FIG. 6 is a top view of the retractable bayonet shown in FIG. 1;

FIG. 7 is a bottom view of the retractable bayonet shown in FIG. 1;

FIG. 8 is a perspective view of a retractable bayonet in an extended configuration;

FIG. 9 is a front elevational view of the retractable bayonet shown in FIG. 8;

FIG. 10 is a rear elevational view of the retractable bayonet shown in FIG. 8;

FIG. 11 is a left side elevational view of the retractable bayonet shown in FIG. 8;

FIG. 12 is a right side elevational view of the retractable bayonet shown in FIG. 8;

FIG. 13 is a top view of the retractable bayonet shown in FIG. 8; and,

FIG. 14 is a bottom view of the retractable bayonet shown in FIG. 8.
